UNITED STATES PATENT OFFICE.

ISAAC C. POPPER, OF NEW YORK, N. Y., ASSIGNOR TO THE THEROZ COMPANY, OF NEW YORK, N. Y., A CORPORATION OF DELAWARE.

DESIGN FOR A CAN.

58,628.

Specification for Design.

Patented Aug. 2, 1921.

Application filed December 12, 1919. Serial No. 344,480. Term of patent 14 years.

To all whom it may concern:

Be it known that I, ISAAC C. POPPER, a citizen of the United States, residing at New York city, in the county of New York and State of New York, have invented a new, original, and ornamental Design for a Can, of which the following is a specification, reference being had to the accompanying drawing, forming part thereof.

The figure is a perspective view of a can, showing my new design.

I claim:

The ornamental design for a can, as shown.

ISAAC C. POPPER.
